UNITED STATES PATENT OFFICE.

S. JARVIS ADAMS, OF PITTSBURG, PENNSYLVANIA.

PUMP-SPOUT.

SPECIFICATION forming part of Letters Patent No. 259,451, dated June 13, 1882.

Application filed April 5, 1882. (No model.)

To all whom it may concern:

Be it known that I, S. JARVIS ADAMS, of Pittsburgh, in the county of Allegheny and State of Pennsylvania, have invented a new and useful Improvement in Pump-Spouts; and I do hereby declare the following to be a full, clear, and exact description thereof, reference being had to the accompanying drawings, forming a part of this specification, in which—

10 Figure 1 is a perspective view of a pump, showing my improved spout. Fig. 2 is a longitudinal section thereof. Figs. 3 and 4 are perspective and sectional views, respectively, of the securing-plate. Figs. 5 and 6 are perspective and sectional views, respectively, of the securing-plate where the thread is formed sectional; and Fig. 7 is a side view of the spout, having lugs with which the sectional thread of the plate engages.

20 Like letters of reference indicate like parts in each.

My invention relates to the metal spouts used with wooden pumps, and has special reference to the means for securing the spout to the pump. Heretofore these spouts have been secured to the pumps by means of a screw-threaded extension which screwed into a hole bored in the pump. It has been found that the water would sink into the wood surrounding this extension, and, saturating it, soon cause it to decay, so that the thread in the wood was not sufficiently strong to support a bucket or other receptacle hung on the end of the spout, and it would be pulled out from the pump by the weight of the bucket. To overcome this difficulty a rim or flange has been cast around the spout in front of the extension, and screws passed through the flange into the body of the pump, thus supporting the spout at a distance from the spout-hole. These flanges are, however, exceedingly difficult to cast true, requiring the work of highly-skilled molders, and being also often disfigured by fins at the joining of the mold, and on account of the metal not filling the entire cavity of the rim. They also necessitated the removal of the securing-screws to remove the spout, as is sometimes desired for packing, to attach a hose to the pump, or for other reasons.

50 The object of my invention is to form a spout having a bracing-plate by which it is secured

to the pump, and from which the spout can be removed for packing or other purposes without the removal of the plate from the pump.

It consists essentially in combining with 55 the spout an annular securing-plate adapted to pass over the extension at the back of the spout, and be secured thereon in such manner that it gives a strong brace between the spout and the pump, and at the same time permits 60 the removal of the spout without unscrewing the plate from the pump.

To enable others skilled in the art to make and use my invention, I will describe its construction and manner of use.

In the drawings referred to, A represents a common wooden pump, to which my improved spout B is secured. The spout is generally made of cast-iron, and has the downwardly-extending mouth b and the lug c, on which the bucket 70 or other receptacle is hung during filling. At the back of the spout is the annular shoulder d and the cylindrical extension e, this extension being threaded to screw into the pump-hole or not, as desired.

75 My improved securing-plate F is annular in form, and has a series of screw-holes, f, through which screws pass to attach the plate to the pump. The inner edge of the plate is screw-threaded, as at g, a single thread only being 80 generally formed around the edge, as this gives as strong a connection as is necessary, and the plate can be easily cast, the beveled edge of each side of the thread being formed in each half-mold, so that no coring or thread-cutting 85 is necessary. Where a thread is cast along the entire surface of the extension e the thread on the plate corresponds thereto, and where the extension is plain a short thread is formed close to the shoulder d. Instead of making a 90 single thread, g, on the inner edge of the plate, a sectional thread may be formed thereon, as shown in Figs. 5 and 6, and lugs k, corresponding in number to the number of divisions in the sectional thread, be formed on the 95 extension e of the spout near the annular shoulder, as shown in Fig. 7.

In securing the spout to the pump the securing-plate F may either be first fastened around the pump-hole by means of screws passing 100 through the holes f, and the spout afterward screwed into it, or it may be screwed securely

to place around the extension *e* against the shoulder *d*, and afterward attached to the pump-body, the latter being preferred. As it is firmly secured to the spout and rigidly attached to the pump-body by the screws around and some distance from the pump-hole, it forms a strong and lasting connection between them, which will not be affected or loosened by the decaying of the wood around the spout-extension. It also permits the spout to be easily and rapidly removed by unscrewing, without the removal of the plate, for packing, to insert a hose, or for any other reason, and to be as rapidly replaced, and thus overcomes all the objections to the former means for connecting the spout to the pump.

What I claim as my invention, and desire to secure by Letters Patent, is—

1. In combination with a pump-spout hav-

ing an annular extension at the back thereof, 20 an annular bracing-plate adapted to be secured from the back on the extension of the spout and be attached to the pump-body, substantially as and for the purposes set forth.

2. In combination with a pump-spout hav- 25 ing at the back thereof an annular extension and shoulder, an annular bracing-plate adapted to screw from the back over the extension against the shoulder and be attached to the pump-body, substantially as and for the pur- 30 poses set forth.

In testimony whereof I, the said S. JARVIS ADAMS, have hereunto set my hand.

S. JARVIS ADAMS.
